UNITED STATES PATENT OFFICE.

GEORGE MARSHALL, OF FREMONT, NEBRASKA.

STEAM-BOILER.

No. 809,517.

Specification of Letters Patent.

Patented Jan. 9, 1906.

Application filed June 12, 1905. Serial No. 264,827.

To all whom it may concern:

Be it known that I, GEORGE MARSHALL, a citizen of the United States, residing in Fremont, in the county of Dodge and State of 5 Nebraska, have invented certain new and useful Improvements in Steam-Boilers, of which the following is a specification.

My invention relates to steam-boilers of the class in which fire-tubes which pass horizontally through the boiler are connected at their ends to the boiler-heads, and the principal object of my invention is to provide a strong and durable connection between the tubes and the boiler-heads and to prevent 15 leakage.

In carrying out my invention the ends of the fire-tubes are connected to the boiler-heads in the usual way, and to the rear head next the fire-box I attach a protecting-plate, 20 which is formed with holes registering with the tubes and which is calked to the boiler-head around its entire exterior edges and also around the holes which register with the fire-tubes, so as to secure each tube to the head 25 by an annular calk formed in the protecting-plate. As an additional protection I cover the plate with a protecting-wall constructed of sectional tiles so formed as to be easily put together and taken apart and which may be 30 readily secured to the protecting-plate or detached therefrom.

In the accompanying drawings, Figure 1 shows a vertical section of a portion of a steam-boiler with my improvements applied. Fig. 2 shows an end elevation thereof. Fig. 3 shows an end elevation with the sectional tile protecting-wall removed. Fig. 4 is a detail view illustrating the relation of the protecting-plate, the boiler-head, and the metallic frame of the protecting-wall. Fig. 5 shows 35 an end elevation of the boiler with my improvements applied and with parts of the protecting-wall detached. Fig. 6 shows a vertical section on the line 6 6 of Fig. 5. Figs. 40 7 to 11, inclusive, illustrate in perspective the forms of the several parts of the protecting-wall. Fig. 12 is a detail view, on an enlarged scale and in section, illustrating the manner in which the protecting-plate is 45 calked upon the ends of the fire-tubes. Figs. 50 13, 14, and 15 are perspective views of the several parts of the metallic frame of the protecting-wall.

The boiler A, fire-tubes B, and boiler-head 55 C are of usual construction. The fire-tubes have their ends projecting through the head

C and spun over, as indicated at *x* in Fig. 12. This is a usual way of connecting fire-tubes to a boiler-head, but one which permits leakage, owing to the expansion and contraction 60 of the metal next to the fire-box. In order to provide a strong and durable connection and to prevent leakage, I employ a protecting-plate D, which is made of comparatively thick metal and is secured by bolts *d* and nuts 65 *d'* to the head C. This plate is calked around its edges at *y* to the boiler-head C, and any leakage that may occur will ordinarily be confined between the plate and the boiler-head. The plate D is formed with openings 70 E registering with the tubes B. Preferably the walls of these openings are beveled at *e*, so as to permit of their being calked at *e'* to thereby clamp the spun ends of the tubes and to make a tight joint, preventing or impeding any leakage. It will thus be seen 75 that the plate is firmly united to the boiler-head, it is calked around its edges, and each tube has its end connected with the plate by an annular calking. This protecting-plate 80 is very efficient without further protecting means; but I prefer to employ also a protecting-wall F, composed of fire-brick or tile. This protecting-wall is made in sections, so that it may be easily set up or taken apart, 85 and it is held in place in front of the protecting-plate by means of metallic frame-pieces G H I. (Illustrated in Figs. 13, 14, and 15.)

The frame-piece G consists of a cross-piece *g*, which stands out from the boiler-head C, 90 and feet or standards *g'*, which are attached to the boiler-head in the manner illustrated in Fig. 3, just above the plate D. The frame-piece H comprises a cross-piece *h*, extending from opposite sides of a central piece *h'*, which latter is arranged horizontally and is provided at its inner end with a vertical flange *h*², which is attached to the plate D about midway between its upper and lower ends. The flange *h*² is notched or formed with recesses at *h*³ to accommodate the nuts *d* and to uncover the openings in the tubes B. The frame-piece I (shown in Fig. 15) comprises a base *i*, which is attached to the plate D near its lower end, a body portion *i'*, which projects 95 horizontally from the plate, and a flange *i*², which is turned downward. The frame-piece G is secured to the head C at *c*. The frame-piece H is secured to the plate at *c'*, and the frame-piece I is attached to the plate at *c*². 100

The protecting-wall comprises four principal parts or sections J J' K K' and six smaller

parts L L' M M' N N'. The parts J J' K K' are formed with holes $j k$, registering with the holes in the plate D. The parts J J' are formed to approximately cover the upper half of the plate D, while the parts K K' are formed to approximately cover the lower part of the plate D. The form of the outside of the sections J J' K K' is clearly indicated in Fig. 5, while the interior construction is shown in Figs. 8 and 10. The sections J J' are formed in their upper walls with slots P, extending from the top inwardly. These slots receive the frame-piece G, and these sections J are recessed to receive the plate D—that is, they are formed with flanges p , which overlap the edges of the plate. They are also formed with recesses p' to receive the sections L, which are illustrated particularly in Fig. 7. The sections K K' are formed with flanges k , which overlap the edges of the plate D, with recesses k' , which engage the flange j^2 , and with slots k^3 , which engage the cross-piece H. All the sections J J' K K' are recessed at q to accommodate the heads d' of the bolts d . These main sections are first connected with the frame-pieces G H I in the manner specified, and then these frame-pieces are attached to the plate D by the devices $c c' c^2$. Then the parts L M N are put in place. The parts L are inserted in the recesses p' by being shoved back into them, the inner ends of the parts L being recessed at l to accommodate the securing devices c . The parts M are then moved horizontally or laterally inward in the manner indicated by the arrows in Fig. 5. These sections M M' have flanges m overlapping the plate D, and they are formed with suitably-shaped recesses m' to provide a sliding connection with the frame-piece H. The form of the recesses m' is illustrated in Fig. 9. The sections N N' are assembled by being moved laterally in the direction indicated by the arrows in Fig. 5. They have flanges n , covering the edges of the plate D, and they are formed with grooves n' to connect with the frame-piece I. It will be seen, therefore, that the protecting-wall has four main parts which are connected with three frame-pieces that are attached to the plate D and the boiler-head, the sections being provided with recesses or openings to permit of the securing devices being applied and tightened. In Fig. 5 it will be observed that all of the securing devices are exposed. These are, however, covered by the sections L M N, which are inserted in the manner specified

and which when inserted are held firmly in place, the parts L L' resting on the sections J J', the sections M M' resting on the sections K K' and also being interlocked with the frame-piece H, while the sections N N' are interlocked with the frame-piece I. In this way a protecting-wall of tile or fire-brick is presented to the direct action of the flame or products of combustion and the connection between the tubes and the boiler-head and the protecting-plate is preserved. There are other ways of forming a protecting-wall for the plate D; but that shown is preferred. The details of construction may of course be somewhat varied.

I claim as my invention—

1. A steam-boiler having its fire-tubes projecting beyond the tube-sheet and beaded as described, and a metallic protecting-plate resting in close contact with the tube-sheet, and having holes registering with the tubes, the walls of the holes being formed to closely surround the beaded ends of the tubes, being flared or inclined outwardly and inclined or curved inwardly by being calked around the beaded ends of the tubes to tightly fit them.

2. The combination of a tube-sheet, fire-tubes projecting therethrough and beaded as described, a protecting-plate secured to the tube-sheet, being in close contact therewith and having holes registering with the tubes, the walls of the said holes being formed to fit the beaded ends of the tubes and being calked thereto to make a tight joint, and a protecting-wall made in separable flanged sections, applied to the plate and completely covering its front face and its four edges.

3. The combination of the boiler-head, the fire-tubes, the protecting-plate secured to the boiler-head, the metal frame-pieces attached to the plate and the sectional protecting-wall connected with the frame-pieces.

4. The combination of the fire-tubes, the boiler-head, the protecting-plate attached thereto, the frame-pieces attached to the plate and the protecting-wall having interlocking connections with the frame-pieces and recesses to expose the fastening devices of the frame-pieces, and the wall-sections for filling said recesses.

In testimony whereof I have hereunto subscribed my name:

GEORGE MARSHALL.
